UNITED STATES PATENT OFFICE.

ALFRED C. O. BOCK, OF BROOKLYN, NEW YORK, ASSIGNOR TO RUDOLPH F. EMMERICH, OF BROOKLYN, NEW YORK.

COIN-CONTROLLED VENDING-MACHINE.

No. 907,449.

Specification of Letters Patent.

Patented Dec. 22, 1908.

Application filed August 15, 1908. Serial No. 448,601.

To all whom it may concern:

Be it known that I, ALFRED C. O. Bock, a subject of Germany, and a resident of Brooklyn, in the county of Kings and State of New York, have invented certain new and useful Improvements in Coin-Controlled Vending-Machines, of which the following is a specification.

The invention relates to improvements in coin-controlled vending machines, and consists in the novel features, arrangements and combinations of parts hereinafter described, and particularly pointed out in the claims.

The invention pertains more particularly to novel goods-ejector mechanism, and in accordance with my invention this mechanism comprises a rotary frame or wheel having pockets to receive the coins and temporarily expose the middle portions of the latter and a manually operative plunger rod which when driven inwardly, after a coin has been fed to said frame, will engage the coin and by pressing against the same rotate said frame to a limited extent and cause fingers thereon to move against and eject the bottom piece of a stack of confections held within the machine. In the absence of a coin in the pocket of the rotary frame in line with the plunger rod, the latter if pushed inwardly will pass idly between the sides of said frame without rotating it; the presence of a coin in the pocket of the rotary frame in line with the plunger rod is therefore necessary to enable said rod when pushed inwardly to effect a rotary movement of said frame and cause the latter to eject a piece of the confections from the stack thereof.

The invention will be fully understood from the detailed description hereinafter presented, reference being had to the accompanying drawings, in which:

Figure 1 is a vertical longitudinal section through a coin-controlled vending machine constructed in accordance with and embodying my invention, the section being on the dotted line 1—1 of Fig. 2; Fig. 2 is a horizontal section of the same on the dotted line 2—2 of Fig. 1; Fig. 3 is a vertical longitudinal section through a portion of the same on the dotted line 3—3 of Fig. 2; Fig. 4 is a substantially vertical section through a portion of the same on the dotted line 4—4 of Fig. 3, and Fig. 5 is an enlarged transverse section through the coin chute on the dotted line 5—5 of Fig. 1.

In the drawings, 15 designates a general form of cabinet, 16 a vertical holder or tray of customary form and construction for holding the stack of pieces 17 of confection to be sold, 18 a manually operative plunger-rod, 19 a rotary goods-ejector wheel or frame, 20 a coin-chute leading from the entrance coin-slot 21 to said ejector for directing coins thereto, 22 a plate at the base of said holder and less in width than the same for supporting the stack of confections and directing the ejected pieces thereof to the discharge chute 23 therefor, and 24 a plate to receive the coins which may fall by gravity from said ejector and direct them frontwardly from below the same.

My invention resides more particularly in the rotary goods-ejector 19 and parts necessarily co-operating therewith.

The plunger 18 is a plain rod slidably mounted in apertured hangers 25 secured to a supporting plate 26 for the operative mechanism. Upon the rod 18 is provided a coiled spring 27 held under compression between one of the hangers 25 and a collar 28 fastened on said rod. The purpose of the spring 27 is to normally retain the rod 18 in its initial projected position shown in the drawings and to return said rod to such position after it has been forced inwardly for the purpose of effecting the ejection of a piece of the confections.

The goods-ejector 19 is rotatably mounted in bearings 29 supported from the plate 26 and comprises a hub 30, shaft 31 and sides 32, 33, and said ejector is preferably formed on one side with a star ratchet-wheel 34, more clearly illustrated in Fig. 1, for co-operation with a spring 35 flexed against it and adapted to yieldingly retain it in stationary position. The purpose of the star-wheel 34 and spring 35 is to yieldingly lock the goods-ejector 19 in stationary position at the end of each of its operative movements. The sides of the goods-ejector 19 are formed of corresponding radial arms or members in whose inner faces are formed radial grooves 36 which form pockets to receive the coins 37 fed to the machine, said grooves 36 being preferably wider at their outer ends and thence narrowing toward the hub 30, as shown in Fig. 3. The sides of the ejector 19 are separated from each other by a space, as shown in Fig. 4, and when a coin 37 is fed to one of the pockets formed by the facing 110

grooves 36 it will span said space, as shown in the upper part of Fig. 4, and have its opposite then substantially vertical edges held within said grooves, the then lower end of the coin resting against the hub 30, as indicated in Figs. 3 and 4. In the present instance I illustrate the sides of the ejector 19 as being formed with six radial arms or members containing in their inner faces the corresponding radial grooves 36, and hence the star-wheel 34 is formed with six points. The radial members constituting the sides of the ejector 19 are formed at one side of the grooves 36 with outwardly projecting extensions or fingers 38 which serve as guides to direct the coins from the chute 20 into the pockets of the ejector (Fig. 3) and also as means, during the rotation of the ejector, for engaging the front vertical edge of the bottom piece 17 and pushing the same from the tray or holder 16, said ejected piece 17 sliding down the plate 22 and falling on the chute 23, which will direct it to the usual front opening at the lower end of the cabinet 15. The plate 22 is less in width than the tray or holder 16 and supports the vertical central portion of the stack of pieces 17. During the rotation of the ejector 19, the fingers 38 pass along opposite sides of the plate 22 and engage the end portions of the pieces 17.

The ejector 19 serves to receive and temporarily hold the coins 37 and the radial arms or members of its sides, in which the pockets for the coins are formed, are adapted to substantially straddle the lower end of the tray or holder 16, as shown in Fig. 3, so that during each operative movement of the ejector a pair of the fingers 38 will pass from position adjacent to the lower end of the coin-chute 20 to a position just in rear of the lower end of the tray or holder 16, the ejector during such movement performing one-sixth of a rotation and being then yieldingly locked by the engagement of the spring 35 with the star-wheel 34. The goods ejector 19 is below the holder or tray 16 and its upper portion is in line with the plunger 18, the purpose being that when no coin 37 is in the pocket of the ejector in line with the coin-chute 20, the plunger rod, if driven inwardly, will pass through the space between the sides of the ejector 19 and not operate the latter. When a coin 37 is in the pocket of the ejector in line with the chute 20, as shown in Fig. 3, the inner end of the plunger 18, if pushed inwardly, will move against said coin, and, by pressing against the latter, cause the ejector to perform one-sixth of a rotation, the fingers 38 at said pocket holding the coin, moving against the bottom piece 17 of the confections and dislodging it from the holder 16 during such partial rotation of the ejector.

65 The operation of the machine will be un-

derstood from the foregoing description without further extended explanation. The normal position of the parts of the machine are shown in Fig. 3, and it is represented that a coin 37 has been fed to one pocket of the 70 ejector preparatory to the plunger rod 18 being pressed inwardly. The purchaser after feeding a coin to the chute 20 will press the rod 18 inwardly and the inner end of this rod will move against the coin and cause the 75 ejector to perform one-sixth of a rotation and while doing so operate through the fingers 38 to eject the bottom piece 17 of the confections, said piece descending over the plate 22 and down the chute 23. The spring 80 27 will return the rod 18 to its outer or initial position. At the end of each movement of the ejector another pocket thereof will pass into line with the coin chute 20. The coins will remain in the pockets of the ejector 19 85 until permitted to slide therefrom by gravity, as I indicate by dotted lines at the right hand portion of Fig. 3.

What I claim as my invention and desire to secure by Letters Patent, is:

90 1. In a coin-controlled vending machine, a vertical holder for a stack of the goods to be sold, a goods ejector located below said holder, a coin-chute for directing the coins thereto and rendering the same operative, a 95 manually operative plunger for coöperation with said ejector, and means at the lower end of said holder to support the stack of goods normally free of said ejector, said ejector comprising a rotary frame having radial 100 pockets between its sides to receive the individual coins and hold the same exposed to the inner end of said plunger and which sides are provided with radial fingers projecting therefrom to engage, when the frame is rotated by the pressure of said plunger against a coin held thereby, the vertical side of the lower piece of goods in said holder and push the same therefrom; substantially as set forth.

110 2. In a coin-controlled vending machine, a vertical holder for a stack of the goods to be sold, a goods ejector located below said holder, a coin-chute for directing the coins thereto and rendering the same operative, a 115 manually operative plunger for coöperation with said ejector, and means at the lower end of said holder to support the stack of goods normally free of said ejector, said ejector comprising a rotary frame having radial 120 pockets between its sides to receive the individual coins and hold the same exposed to the inner end of said plunger and which sides are provided with radial fingers projecting therefrom to engage, when the frame is rotated by the pressure of said plunger against a coin held thereby, the vertical side of the lower piece of goods in said holder and push the same therefrom, and said fingers being at 125 the front sides of said pockets so as to aid in 130

directing the coins from said chute to said pockets; substantially as set forth.

3. In a coin-controlled vending machine, a vertical holder for a stack of the goods to be sold, a goods ejector located below said holder, a coin-chute for directing the coins thereto and rendering the same operative, a manually operative plunger for coöperation with said ejector, and means at the lower end 10 of said holder to support the stack of goods normally free of said ejector, said ejector comprising a rotary frame having radial pockets between its sides to receive the individual coins and hold the same exposed to 15 the inner end of said plunger and which frame is provided with radial fingers projecting therefrom to engage, when the frame is rotated by the pressure of said plunger against a coin held thereby, the vertical side 20 of the lower piece of goods in said holder and push the same therefrom, said fingers being spaced to straddle the lower end of said holder after each operation of the machine; substantially as set forth.

25 4. In a coin-controlled vending machine, a holder for the goods to be sold, a goods-ejector below the same, a chute for directing the coins thereto and rendering the same operative, and a manually operative plunger 30 for coöperation with said ejector, said ejector comprising sides grooved at their inner faces to form pockets to receive the edges of the individual coins and hold the coins exposed to the inner end of said plunger and which 35 sides are provided with fingers to engage, when the frame is rotated by the pressure of said plunger against a coin held thereby, the lower piece of goods in said holder and push the same therefrom, and said pockets and 40 fingers of said ejector being spaced so that each two pockets will straddle the lower end of said holder; substantially as set forth.

45 5. In a coin-controlled vending machine, a holder for the goods to be sold, a goods-ejector below the same, a chute for directing the coins thereto and rendering the same operative, and a manually operative plunger for coöperation with said ejector, said ejector comprising sides grooved at their inner faces

to form pockets to receive the edges of the 50 individual coins and hold the coins exposed to the inner end of said plunger and which sides are provided with fingers to engage, when the frame is rotated by the pressure of said plunger against a coin held thereby, the 55 lower piece of goods in said holder and push the same therefrom, and said pockets and fingers of said ejector being spaced so that each two pockets will straddle the lower end of said holder, combined with means for arresting said frame after each operation thereof with one of its pockets in position to receive a coin from said chute; substantially 60 as set forth.

6. In a coin-controlled vending machine, 65 a holder for the goods to be sold, a goods-ejector below the same, a chute for directing the coins thereto and rendering the same operative, and a manually operative plunger 70 for coöperation with said ejector, said ejector comprising sides grooved at their inner faces to form pockets to receive the edges of the individual coins and hold the coins exposed to the inner end of said plunger and which 75 sides are provided with fingers to engage, when the frame is rotated by the pressure of said plunger against a coin held thereby, the lower piece of goods in said holder and push the same therefrom, and said pockets and 80 fingers of said ejector being spaced so that each two pockets will straddle the lower end of said holder, combined with means for arresting said frame after each operation thereof with one of its pockets in position to receive a coin from said chute, and a plate at 85 the base of said holder to support the stack of goods therein, said plate being less in width than said holder and extending rearwardly therefrom to direct the ejected goods to the discharge therefor; substantially as 90 set forth.

Signed at New York city, in the county of New York, and State of New York, this 14th day of August, A. D. 1908.
